UNITED STATES PATENT OFFICE.

FREDERICK C. FESENBEK, OF PHILADELPHIA, PENNSYLVANIA, ASSIGNOR, BY MESNE ASSIGNMENTS, TO HOWARD SMALL AND ALEXANDER H. BOYD, RECEIVERS OF KELLER MANUFACTURING COMPANY.

ROTARY PNEUMATIC PUMP.

1,091,821.

Specification of Letters Patent. Patented Mar. 31, 1914.

Application filed September 11, 1911. Serial No. 648,666.

To all whom it may concern:

Be it known that I, FREDERICK C. FESENBEK, of Philadelphia, in the county of Philadelphia and State of Pennsylvania, have invented certain new and useful Improvements in Rotary Pneumatic Pumps, whereof the following is a specification, reference being had to the accompanying drawings.

By the phrase "rotary pneumatic pump", I mean to include both rotary suction pumps and rotary blowers, of the type in which blades rotate within a cylinder within which a hollow drum turns eccentrically, the blades passing through slots in the periphery 15 of the drum and accommodating themselves to its motion. The periphery of the drum is contiguous to the periphery of the cylinder, at one point of the latter, and intake and outlet orifices are provided one on either side 20 of this point of contact. Such a rotary pneumatic pump may be used to create suction in connection with pneumatic cleaning apparatus or it may be used as a blower.

My invention relates particularly to the 25 construction of the blade, and consists in supplementing its plate with a resilient lamina mounted fixedly in relation to the blade with a space intervening. When this 30 plate and its lamina are received within the slot provided for them in the drum, a slight pressure is exerted, tending to press the two together. The resiliency of the lamina resists this pressure and keeps the external 35 surfaces of the plate and the lamina in close contact with the corresponding edges of the slot in the drum.

I have illustrated a convenient embodiment of my invention in the accompanying drawings, in which—

40 Figure I, is an elevation (with one end removed), of a pneumatic pump embodying my invention. Fig. II, is a perspective view of one of the blades.

The pump comprises the cylindrical casing 1, closed at both ends, which may be termed simply the cylinder. The fixed shaft 2, occupies the central axis of the pump. The cylinder is provided with an intake passage 3, and outlet passages 4, which, as 50 shown in the drawings, are protected by a muffler 5. A drum 10, is mounted within the cylinder so as to turn eccentrically therein, with its periphery always in contact at the point 11, with the inner surface of the

cylinder, the point 11, being about mid-way 55 between the intake 3, and the outlet 4. The drum 10, is provided with peripheral slots 12, 12, through which pass blades 13, which are pivoted upon the shaft 2, and reach to the inner periphery of the cylinder. Thus 60 far I have described the elements common to pumps of this character, it being understood that the number of blades and other details may vary.

Each of the blades comprises a hinge portion 15, the collar of which surrounds and rotates upon the shaft 2, and also a plate 16, which is received in a slot 17, within the hinge portion. There is also fastened to the hinged portion, preferably by the same 70 rivets by which the plate 16, is held within its slot, a lamina 18, of the same outline as the plate 16, and parallel to it with a small intervening space. This lamina 18, is of resilient material preferably of steel and by 75 reason of the space between it and the plate 16, is capable of offering resistance to any compressive force, tending to thrust the two together. If desired, the plate 16, may be resilient, as well as the lamina 18, but I 80 prefer that the resiliency should chiefly reside in one of the two parts.

The slot 12, in the drum 10, through which the blade passes has its edges beveled in both directions as shown, in order to the better accommodate the varying positions in which the blade lies in relation to it. The edges of this slot are so spaced as to place a slight but sufficient pressure upon the outer surfaces of the plate with its lamina where they pass 90 through it, this pressure slightly pushing the lamina toward the plate as permitted by the interspace. The plate and its lamina are of the same shape and area, both completely filling the space within the cylinder 95 between its periphery and the central axis, and for pumping or blowing purposes the plate and its lamina act substantially as one blade.

The method of operation of the pump 100 thus described is well known. By my invention there is secured the additional advantage of continuous resistance by the plate and its lamina to the compressive force exerted by the opposed edges of the slot 12, which 105 maintains a very close contact between said edge of the slot and the contiguous portions of the blade, notwithstanding the rapidly

varying relation of the two parts. I thus secure a better air-tight contact at this point than has heretofore been obtained in pumps of this character. Also the joint is a noiseless one, the constant pressure preventing rattling.

Having thus described my invention, I claim:

A rotary pneumatic pump, including in combination a cylinder, a slotted drum mounted eccentrically and rotating in said cylinder, blades mounted concentrically of said cylinder and extending through the slots in said drum, each of said blades com-

prising a plate and a parallel lamina with 15 an interspace, whereby said lamina is free of said plate, the lamina being sufficiently resilient whereby said plate and lamina are held continually in contact with the respective adjacent side edges of the slot in the 20 drum, through which the blade passes.

In testimony whereof, I have hereunto signed my name at Philadelphia, Pennsylvania, this eighth day of September, 1911.

FREDERICK C. FESENBEK.
